UNITED STATES PATENT OFFICE.

ERNEST ROSS, OF NEWARK, NEW JERSEY, ASSIGNOR TO GENERAL ELECTRIC COMPANY, A CORPORATION OF NEW YORK.

VERNIER DRIVE.

Application filed December 27, 1924. Serial No. 759,475.

My present invention relates to a driving apparatus whereby a movement of a driving member produces a relatively smaller movement of a driven member, and more particularly to so-called vernier drive apparatus such as is frequently employed for accurate tuning of electric circuits.

The object of my invention is to provide an apparatus of the class described which will be simple in its construction and positive in its action for driving a rotating member in either direction and which at the same time will permit of any desired reduction in speed between the driving member and the member to be driven.

The novel features which I believe to be characteristic of my invention are set forth with particularity in the appended claim. My invention, itself, however both as to its organization and method of operation will best be understood by reference to the following description taken in connection with the accompanying drawing in which Fig. 1 is a sectional view of an apparatus embodying my invention; Fig. 2 is an end view of the driving portion thereof; Fig. 3 is a diagrammatic representation of a portion of the driving mechanism to illustrate the principle of the operation thereof; Fig. 4 is a sectional view of a modified form of my invention and Fig. 5 is a diagrammatic representation of the driving mechanism of the form of my invention shown in Fig. 4.

I have indicated in Fig. 1 the application of my invention to a variable condenser of the general type commonly used in radio communication or for similar purposes. This comprises a series of stationary plates 1 which are secured in a frame work comprising end members 2 and 3 by means of a screw-bolt 4. The rotating plates 5 of the condenser are mounted upon a hollow shaft 6 being suitably spaced by means of spacing blocks 7 and secured by means of a nut 8. Extending through the hollow shaft 6 is a driving shaft 9 having at its end the usual operating knob 10. The rotating member of the condenser is associated with driving shaft 9 through the medium of a plurality of balls 11. I have indicated in the drawing three of these balls though, of course, a greater number may be employed if desired. Balls 11 are retained between two concentric races, the outer race 12 is secured to a member 13 which in turn is secured by means of nut 14 to the

driving shaft 9. The inner race which is in the form of a groove is made up of two parts. The part 15 is secured to the end piece 3 of the condenser by means of a nut 16. The second part 17 of the inner race is adjustable in order that the balls may be in good contact with both races at all times. The spring 18 which is located between the part 17 and the end piece 3 of the condenser provides for the desired adjustment of the part 17.

A retainer 19 in the form of a cylindrical member, having slots 20 cut therein for receiving the balls 11, is secured to the end of the hollow shaft 6.

When the shaft 9 is rotated the outer race 12 is rotated therewith and this causes the balls 11 to rotate. At the same time the balls move circumferentially in the groove which constitutes the inner race. It will be noted that the two sides of the inner race are inclined toward one another at an angle, indicated in Fig. 3 as α so that the balls make contact with the two sides of the groove at points 21 which are connected less than 180° apart along the circumference of the balls. As a result each ball rotates with respect to the outer race around a radius equal to the radius of the ball but it rotates with respect to the inner race around a radius equal to the distance indicated on the drawing by the "a". As a result when the outer race moves a distance equal to the circumference of the ball, the ball travels circumferentially along the inner race a distance only equal to the circumference of a circle having radius "a". By suitable selection of the angle of inclination α this distance may be made materially less than the distance of travel of the outer race 12. That is, the smaller angle α is made, the greater will be the ratio between the distances traveled by the outer race and by the balls along the inner race. As the balls travel circumferentially in the inner race, they carry with them the retainer 19 and thus impart motion to the driven shaft 6.

In the modification shown in Fig. 4 of the drawing, the same principle is employed in a slightly different way. In this case the knob 10 is attached to a short driving shaft 6', the end of which carries inner race 22. A ball retainer 23 which is of similar form to that shown in Fig. 1 is secured to the end of the shaft 24 which carries the movable plates 5 of the condenser. In this case the outer race

25 is made up in the same way as the inner race of the modification shown in Fig. 1, a spring 26 serving to adjust the movable portion 27 of the outer race to keep the balls in good contact with the two races. The ratio between the distances of travel of the driving member and the member driven in this case, as in the form shown in Fig. 1, depends upon the angle α . A greater ratio in speed reduction however may be obtained with this form because of the fact that the circumference of the race carried by the driving member is much less than in the form shown in Fig. 1. Hence other dimensions being similar, one turn of the knob 10 in the form shown in Fig. 4 will produce a much smaller movement of the driven member than in the form shown in Fig. 1.

While I have shown and described the preferred embodiments of my invention, it will be apparent that many modifications may be

made in the structure and arrangement of the various parts used as well as in the practical application of my invention without departing from the scope thereof as set forth in the claim.

What I claim as new and desire to secure by Letters Patent of the United States, is:

A wireless apparatus comprising a rotatable driven shaft, a panel through which said shaft extends, an indicator member, adjustable means for said shaft, said means comprising an internal friction gear having a knob attached thereto, a stationary friction gear concentric with said internal gear, a plurality of balls interposed between said friction gears, and a retainer member for said balls connected to the driven shaft and to said indicator member.

In witness whereof, I have hereunto set my hand this 18th day of December, 1924.

ERNEST ROSS.
